(57) **CLAIM**

The ornamental design for a clam hinge, as shown and described.

DESCRIPTION

FIG. 1 is a perspective view of our clam hinge;

FIG. 2 is a back view thereof;

FIG. 3 is a top view thereof;

FIG. 4 is a front view thereof;

FIG. 5 is a right side view, the left t view being a mirror image thereof; and,

FIG. 6 is a perspective view similar to FIG. 1 in which one leaf of the hinge has been moved to be perpendicular to the other leaf of the hinge.

1 Claim, 4 Drawing Sheets

FIG. 1

FIG. 2

FIG. 3

FIG. 4

FIG. 5

FIG. 6
